UNITED STATES PATENT OFFICE.

RICHARD C. BECKETT, OF WEST POINT, MISSISSIPPI.

CAR-COUPING.

SPECIFICATION forming part of Letters Patent No. 610,519, dated September 13, 1898.

Application filed October 25, 1897. Serial No. 656,380. (No model.)

To all whom it may concern:

Be it known that I, RICHARD C. BECKETT, residing at West Point, in the county of Clay and State of Mississippi, have invented a new 5 and useful Improvement in Car-Couplings, of which the following is a full, clear, and exact description.

My invention is an improvement in automatic pivoted-jaw car-couplings; and the novelty resides chiefly in the construction and arrangement of the springs and disengaging devices with the jaws, as hereinafter set forth and claimed.

In the accompanying drawings, Figure 1 is 15 an end view of a freight-car having my improved coupling attached. Fig. 2 is a plan view of my coupling. Fig. 3 is a central longitudinal section of the coupling. Fig. 4 is a side view of one of the catches and its attached lever-triggers.

The hollow draw-heads A are rabbeted or halved at their meeting ends, which thus form square abutting edges or surfaces. The draw-heads thus protect the coupling mechanism 25 proper and also take the shock attending collision in coupling cars to which they are respectively connected.

Within each draw-head A a catch B is pivotally mounted on a transverse rod *a*, and 30 their outer ends *b* are beveled and shouldered on the inner side to adapt them to slide into locking engagement, as shown in Fig. 2. Such beveled free end of each catch B is provided with a spring attachment composed of a helical spring C and a hooked rod D, which it encircles. The said rod is permanently connected with the catch B and projects laterally through a hole *a'* in the side of the draw-head, the hooked free end of the same overlapping the edge of such hole, as shown. The 35 spring C seats on a shoulder formed in said hole *a'*. It is apparent that by this construction and arrangement of the spring attachment the free ends of the catches B are pressed 40 inward far enough to cause engagement of the same and to hold them locked against accidental disengagement; also, that the hooks *d* prevent the springs C forcing the catches B inward beyond the point which insures proper 45 sliding engagement of their beveled ends *b*.

To disengage the catches B, as illustrated in Fig. 3, I employ devices in the nature of lever-triggers E, which are straight bars arranged in longitudinal slots *b'* in the catches B and pivoted on cross-pins *e*. A pull-rod F is 55 pivotally connected with the rear end of each trigger and extends through a hole *a''* in the side of a draw-head A, its outer end being in practice connected with another pull-rod or chain, which may extend to the side or top of 60 a car. In Fig. 1 I show a chain G attached and winding on a rotatable vertical shaft H, having a hand-wheel I on each end. This attachment, however, particularly applies to 65 freight-cars.

It will be seen that by the arrangement of the springs C near the front ends of the catches B the springs act with greater power and certainty, and the stop-rods D also serve as holders and guides therefor. Besides, this 70 arrangement leaves space at the rear for application of the pull-rods F, that operate the triggers E. I thus avoid practical defects in 75 couplings of this class in which flat plate-springs are used to act on the rear portion of the draw-heads and in which horizontal rods extend from the side through the catches for operating the triggers.

Having thus described my invention, what 80 I claim is—

The improved car-coupling composed of the hollow draw-heads having their ends halved and forming abutting shoulders, the beveled catches pivoted in the respective draw-heads, the spring attachments of said catches, which 85 consist of hooked stop-rods secured to the free front portions of the catches and extend through adjacent holes in the draw-heads, and helical springs encircling such rods and seated in sockets in the draw-heads, and the lever- 90 triggers composed of straight bars pivoted in a slot in the catches, and pull-rods extending through holes in the draw-heads, as shown and described.

R. C. BECKETT.
